Primary Examiner — Ian Simmons*Assistant Examiner* — Dana L Meyrow*(74) Attorney, Agent, or Firm* — Cantor Colburn LLP(57) **CLAIM**

I claim, the ornamental design for a container with rolled end, as shown and described.

DESCRIPTION

FIG. 1 is an isometric view of the container with rolled end;
FIG. 2 is a front view of the container with rolled end;
FIG. 3 is a rear view of the container with rolled end;
FIG. 4 is a side view of the container with rolled end;
FIG. 5 is the opposite side view of the container with rolled end; and,

FIG. 6 is a top plan view of the container with rolled end.
The broken lines in the FIGS. 1, 2, 4 & 5 drawing views represent a perforation on the sidewall of the container. These broken lines are included in the claimed design.
